Berkeley, Calif., a corporation of California

Application October 10, 1939, Serial No. 298,786

8 Claims. (Cl. 184—6)

This invention relates to a pump drive, and has for one of its objects a right angle pump drive that includes novel means for more efficiently lubricating the working parts. Another object is a simplified construction in a gear drive for pumps for enabling proper assembly of the parts with the desired accuracy with greater efficiency than heretofore. A still further object is improved power transmission means between a pump and motor constructed to reduce the wear in such means and to reduce heating of the elements in such means, and to more efficiently transmit the power from the motor to the pump. A still further object is a power transmission means of the above general character connecting between a motor and pump that readily adapts itself to different conditions encountered in installation with respect to differences in pumps and motors. Other objects and advantages will appear in the description and drawing.

In the drawing,

Fig. 1 is a sectional view through a right angle pump drive incorporating the invention.

Fig. 2 is a plan view of the pump drive, showing the housing more in detail.

In detail, the housing for the working parts of the drive comprises a vertically extending, generally tubular main housing 1 formed with a flange 2 at its lower end for bolting to a floor or foundation in the usual manner, and also formed with a bottom 3. The sides of said main housing are slanted slightly inwardly from the base end toward the upper end, which upper end is closed by a horizontal top 4, preferably formed integrally with the sides of the main housing 1. The top 4 is centrally apertured for supporting ball bearing cage and balls 5 thereon, and a dome-shaped cap 6 extends over the top 4 and upper end of the housing, secured to the housing by bolts 7 adjacent the edges of the dome and housing.

One of the sides of said housing is formed with a relatively large opening, and extending outwardly from the edges of said opening is a cone-shaped bearing support 8, the base of the cone being secured by bolts to the main housing adjacent the edges of the opening and the apex being disposed outwardly of the side of the housing substantially co-axial with the central horizontal axis of said opening. Said cone is horizontally apertured at the apex for receiving a vertically disposed annular ball bearing cage 9, with balls therein.

The side of the housing 1 opposite the cone 8 is formed with a sight opening covered by a glass

10, which glass is removably secured to the housing wall at the edges of said latter opening by a frame 11 in which the glass is secured. A conventional gasket between the frame and housing seals the sight opening against any possible leakage of oil through said opening, while the glass is sealed by any suitable means in the frame against leakage between the glass and frame.

The bottom 3 of the housing is centrally apertured to pass a vertical shaft 12 into said housing with its upper end extending through the central aperture in top 4. Said shaft 12 is disposed within a sleeve or hollow shaft 13, which hollow shaft is secured thereto for rotation therewith by means of a nut 14 threaded onto the uppermost end of said shaft, which nut engages the upper end of a collar 15. Collar 15 is interiorly threaded at its lower end to engage exterior threads on the upper end of the hollow shaft 13, and said collar is also secured to shaft 15 against rotation relative thereto by key 16.

Spaced below the lower end of collar 15 is a bevel gear 17, through which the hollow sleeve 13 passes, and which gear is supported on an upwardly facing shoulder 18 formed by reducing the diameter of the upper end of said hollow shaft to the point of said shoulder.

Between gear 17 and the lower end of the collar 15 is a tubular spacer sleeve 19 surrounding the upper end of hollow shaft 13. This spacer sleeve is of reduced diameter at its upper end portion to fit the inner ring of the ball bearing cage 5, and to form a shoulder on which said inner ring is supported. The radially inwardly facing side of the central aperture in top 4 of the housing is likewise formed to provide an upwardly facing shoulder 20 for supporting the outer ring of cage 5. This spacer sleeve 19 may be formed at its lower end with a radially outwardly projecting flange, or the equivalent thereof in the form of an annular disk 21 may be secured between the lower end of sleeve 13 and the gear 17, as desired. This disk constitutes an oil flinger or distributor, as will later be described.

It will be seen from the foregoing that the shaft 13 may be inserted vertically into the housing 1 through top 4, and with the bevel gear 17, sleeve 19, flinger 21, collar 15 secured on said shaft by collar 15 and the keys 16, 22, said latter key securing said gear on said hollow shaft. The cage 5 is next placed in proper position, after which a cap 23, having downwardly directed sides and a top apertured to rotatably pass collar 15 is positioned over the bearing 5

and the elements disposed inwardly thereof. The lower edges of said sides engage upwardly directed circular flanges 24 formed around the central opening in said top 4, and are fastened together by conventional bolts 25 extending through the margins of said cap, which cap holds bearing 5 and shaft 13 in place.

From the foregoing description it is obvious that the position of gear 17 with reference to the shaft 12 can be very quickly and easily positioned at the desired level within the housing by varying the thickness of spacer or flinger 21.

The cone 8, at its larger end, is formed with a shoulder 26 that is adapted to fit against the outwardly facing sides of the housing around the laterally directed opening therein, said opening being already described. A gasket may of course be interposed between the shoulder and edges of said opening for sealing against oil leakage, the said cone being bolted to the housing 1 by bolts 27.

An annular ring 29 is formed integrally with said cone 8, said ring being connected with the larger diameter end of said cone by a conical web, the said ring being at the smaller diameter end of the web and the larger diameter end being integrally connected with the larger diameter end of cone 8. This web supports ring 29 in position extending inwardly of the larger diameter end of the cone 8, and ring 29 is interiorly machined to receive the outer ring of a ballbearing cage and balls 30. The said web is also formed with an annular row of relatively large openings 31 therein.

Extending through the apertured smaller end of cone 8 and to a point adjacent the hollow shaft 13, is a horizontal shaft 32. This shaft carries at its inner end adjacent shaft 13 a bevel gear 33, which gear is keyed to said shaft 32, the bearing cage 30 being adjacent the side of the gear facing the outer end of said shaft with its inner ring engaging between said gear and a sleeve 34 that is disposed between said inner ring and the inner ring of the ball cage 9, which latter bearing rotatably supplies the shaft in the smaller diameter end of cone 8.

The teeth of gear 33 are adapted to mesh with the teeth of gear 17, and to insure proper meshing of said gears, a washer 35 of the desired thickness is positioned between the outer race of ballbearing 30 and a shoulder 36 formed on ring 29. Thus the accurate positioning of gears 17 and 33 is procured in a simple manner, and once the correct meshing of the gears is made, no further adjustment is necessary.

On the outer end of shaft 32, and adjacent bearing 9, the said shaft is exteriorly threaded for a lock nut 37, and a conventional oil seal 39 seals the smaller diameter end of cone 8 and shaft 32. Nut 37 is conventional, with "S. A. E." lock washer, as indicated.

The shaft 32 projects outwardly of said smaller end of cone 8, and carries a pulley 40, which pulley extends over the diverging sides of said cone 8 with the central plane thereof extending substantially centrally through bearing 9, thus placing the line of force about over said bearing when the pulley is driven by a belt from a source of power, such as a motor (not shown).

The shaft 32 is the drive shaft and shaft 12 is the driven shaft, which latter shaft extends downwardly from the bottom of the housing for driving the pump.

Secured on the lower end of the tubular shaft 13 is a worm pump or pump runner 41, said pump

runner being in the form of a vertically extending cylinder exteriorly threaded at 42 with cylindrically planar flat outer edges on said threads, which edges are adapted to relatively closely seat 5 against the inner cylindrical surface formed in an annular, upstanding flange 43 formed around the central opening in bottom 3, and integrally connected with the latter. This flange 43 projects above said pump member 41, and between the 10 portion so projecting from said member, and the shaft 13, is a ball bearing 44 that rotatably mounts and centers the lower end of shaft 13 with respect to said flange.

The flange 43 is formed at its lower end, and 15 above bottom 3, with a passageway 45 that communicates between the interior of the housing above said bottom 3 and the lower end of the pump runner 41 at a lateral side of said runner. The open end of the passageway 45 is positioned so that the threads at the lower end of said runner will scant said open end upon rotation of the runner 41, and a second passageway 46 in flange 43 similarly communicates at its inner end with the uppermost groove between the threads on said runner 41, which threads terminate short of the upper end of flange 43. The runner 41 is keyed to shaft 13 by key 47, so that runner 41 will rotate with said shaft 13. In the opposite outer open end of passageway 46, is secured one 20 end of a pipe 48 that extends vertically upwardly into the lower open end of a vertical passageway 49 that extends through the top 4 of the housing. Thus upon the lower portion of the housing 1 being filled to point 50 through a filler opening 51, upon rotation of the shaft 13, the oil will be forced upwardly by threads 42 from passageway 45 into the passageway 46 and pipe 48 for discharge into the space 52 over bearing 5 enclosed by cap 23. The oil in said space then passes 25 through bearing 5, lubricating the same, and onto the oil flinger disk 21 which will cause the oil to be thrown laterally against the glass 10 and also through openings 31 to the bearing 9 for lubricating the latter. This oil will then flow 30 through bearing 5, lubricating the same, and onto the oil flinger disk 21 which will cause the oil to be thrown laterally against the glass 10 and also through openings 31 to the bearing 9 for lubricating the latter. This oil will then flow 35 through bearing 5, lubricating the same, and onto the oil flinger disk 21 which will cause the oil to be thrown laterally against the glass 10 and also through openings 31 to the bearing 9 for lubricating the latter. This oil will then flow 40 through bearing 5, lubricating the same, and onto the oil flinger disk 21 which will cause the oil to be thrown laterally against the glass 10 and also through openings 31 to the bearing 9 for lubricating the latter. This oil will then flow 45 through bearing 5, lubricating the same, and onto the oil flinger disk 21 which will cause the oil to be thrown laterally against the glass 10 and also through openings 31 to the bearing 9 for lubricating the latter. This oil will then flow 50 back into the pump at the bottom of the housing for being re-circulated. An operator by observing the glass 10 can readily determine whether or not the oil is being properly circulated for lubricating the bearings and other parts in said housing.

A second passageway 53 in flange 43 at about the same level as passageway 46 communicates with pipe 54, which latter pipe extends upwardly and terminates in an upper open end directed 55 generally toward the juncture of the teeth of gear 17 with the teeth of gear 33. Thus when the pump runner 41 is in operation, oil will be pumped through pipe 54 for discharge against gears 17, 33 for properly lubricating the same, and this oil will drain back into the oil sump.

Surrounding the shaft 12 where the latter passes into the lower end of shaft 13 is a novel oil seal, which comprises a sleeve, or oil seal tube 55 surrounding said shaft 12, and spaced 60 therefrom. This tube 55 is secured at its lower end in a central opening in a closure plate 56, the said plate being secured at its margins to the margins of the central opening in bottom 3. The inside of the lower end of shaft 13 is enlarged to receive said tube with the tube spaced from inner sides of said lower end. The central bore of runner 41 at its lower end is recessed at 58 and in said recess is an "S. A. E." standard lock nut and washer assembly 59 secured to the lower end of shaft 13,

the washer in the assembly being disposed between the nut and the runner. Since the oil level in the sump in the bottom of the housing is at a level below the upper end of the oil seal tube 55, the oil will not pass out of the sump through the space between the tube and the shaft 13.

Referring to the dome 6, and cone 8, the dome 6 is formed exteriorly with ribs 60 in planes extending radially from its central vertical axis and the cone 8 is exteriorly formed with ribs 61 in planes extending radially from its central horizontal axis. The ribs 60 and the ribs 61 function to dissipate the heat developed within the housing.

In operation, when the drive shaft 32 is driven by any suitable connection between the shaft and motor (motor not shown) the shafts 12, 13 will also be rotated and the main pump below the housing, and connected with shaft 12, will be actuated. At the same time the oil runner 41 will forcibly pump oil from the sump in the bottom of the housing to the bearing 5; the flinger disk 21 functioning to insure distribution of the oil to bearings 9, 30, and at the same time throwing the oil on sight glass 10 to enable the operator to determine whether the oil is being properly distributed. The pump runner 41 also pumps oil through the conduit 54 directly to gears 17, 33 some of which oil will fall to bearings 44 for lubricating the same.

Apart from this lubricating system, the provision for quickly and accurately adjusting the gears 17, 33 to mesh properly as by changing the length of spacer sleeve 19 or the thickness of flinger 21, and by changing the thickness of washer 35 is an important feature. Likewise, the oil seal assembly, including tube 55, and the positioning of pulley 40 centrally over bearing 9, and the sight glass, and also the cooling fins or ribs on the dome and cone, are material improvements in pump drives of this character.

Where it is desired to drive the shafts 12, 13 in a direction opposite to the drive established by placing gear 17 above gear 33, provision is made for placing the gear 17 below said gear 33 and keying the gear 17 to shaft 13 as indicated in dotted line at 62, in which case a spacer sleeve indicated in dotted line at 63 may be substituted for the gear 17 between shoulder 18 and flinger 21. Needless to say, flinger 21 may be formed integrally with collar 19, if desired.

It is further obvious that in certain installations the shaft 32 may be directly connected to a motor or to a conventional gear transmission means, thus eliminating the pulley.

Insofar as the pump runner 41 is concerned, in addition to being a positive and extremely simple oil pump in a right angle drive, as disclosed, it is manifest that by merely changing the number and pitch of the threads, any desired flow can be produced.

The head shaft 12 may be raised and lowered to the desired position merely by adjusting nut 14, which latter nut is locked by a lock bar, as indicated, against turning.

Having described my invention, I claim:

1. In a right angle pump drive, including a housing having side walls, a top wall, and a bottom wall, a horizontal drive shaft rotatably extending through said side walls at a point therein, a main shaft rotatably extending through said bottom wall and into said housing, a vertical hollow shaft within said housing into

which the portion of the main shaft within said housing extends, means adjustably securing said main shaft and said hollow shaft together for rotation as a unit, intermeshing gears, respectively, secured on said hollow shaft and said drive shaft for providing a driving connection within said housing between said drive shaft and said hollow shaft, the lower end of said hollow shaft terminating above said bottom wall and adjacent thereto, a vertically extending screw disposed coaxially with the axis of said hollow shaft and secured in position around the lower end thereof, a chamber rigid with said housing having cylindrical inner sides slidably engaging the peripheral surfaces of the screw thread for rotation of the screw within said chamber, the walls of said chamber being ported at vertically spaced points adjacent the upper and lower ends of said thread, said housing communicating with the lower port and a conduit communicating between the upper port and the said gears for conducting oil forced along said screw thread to said gears upon rotation of said screw, said bottom being adapted to support an oil supply with said chamber disposed therein, and an oil seal for preventing oil from leaking from said supply past said vertical shaft at the point where said main shaft passes through the bottom wall, said seal including a vertically disposed tube secured to said bottom wall and disposed around said main shaft and between said main shaft and said hollow shaft, the upper end of said tube terminating at a point above the level of said oil supply.

2. In a right angle pump drive including a housing and a drive shaft and a driven shaft extending perpendicularly to each other into said housing with intermeshing gears secured on said shafts, respectively, within said housing, providing a driving connection between said shafts, said driven shaft being vertically disposed within said housing, a sight opening formed in a side of said housing provided with a transparent closure, said opening being disposed radially outwardly of said driven shaft in a position to enable visual observation of said intermeshing gears and to intercept oil thrown radially outwardly from about the level of said intermeshing gears upon rotation of said driven shaft thereby enabling an operator to visibly observe the degree of lubrication of said gears, and power-driven means for supplying a continuous flow of oil to said intermeshing gears.

3. In a right angle pump drive including a housing having side walls, a top and a bottom, a drive shaft and a driven head shaft extending perpendicularly to each other into said housing, said head shaft being vertical and extending outwardly of the housing through the bottom thereof, a drive gear within said housing secured on said drive shaft, means forming a driving connection between said drive shaft and said driven shaft including a vertical hollow shaft within said housing having a driven gear secured thereon in mesh with said drive gear, means removably securing said hollow shaft to said head shaft with the latter extending into said hollow shaft, pump means at the lower end of said hollow shaft including a pump runner secured to said hollow shaft, a bearing carried by the lower end of said hollow shaft positioning said lower end rotatably in said housing, means positioning said drive gear and said driven gear in mesh with each other, means securing said hollow shaft, driven gear, pump runner and bear-

ing together for removal from said head shaft as a unit.

4. In a right angle pump drive, including a vertical housing having side walls and a bottom wall; a horizontally extending annular flange projecting inwardly from the upper edges of said side walls and carried thereby and a vertically extending annular flange carried by said bottom wall projecting upwardly into said housing; a pair of vertically aligned spaced bearings respectively supported by said horizontal flange and by said vertical flange; a vertical, hollow shaft wholly enclosed within said housing supported for rotation at its upper and lower ends by said bearings and extending above and below said bearings at said upper and lower ends; the inner sides of said vertical flange below the bearing supporting the lower end of said hollow shaft being cylindrical and concentric with said shaft, and a vertical pump runner below said latter bearing embracing and secured to the lower end of said hollow shaft, said runner being exteriorly formed with a helical thread slidably engaging said cylindrical inner sides of said flange for rotation in the latter; a horizontal closure plate generally co-planar with said bottom wall secured to the latter and extending below said runner whereby the runner is wholly enclosed within the cylindrical sides of said flange; a chamber for a supply of oil surrounding said vertical flange and said flange having an upper port and a lower port respectively opening into the portion of the flange embracing said runner at points adjacent the upper and lower ends of said runner, respectively; a conduit outwardly of said hollow shaft extending from said upper port to above said horizontal flange for supplying oil to the bearing carried by said latter flange; said closure below said runner being centrally apertured in axial alignment with said bearings and hollow shaft; a head shaft extending vertically through said central aperture and into said hollow shaft; means securing together the upper ends of said hollow shaft and said head shaft; a bevel gear embracing said hollow shaft between said bearings and rigidly secured to said hollow shaft and a horizontal drive shaft rotatably extending through one of said side walls having a bevel gear on its end within said housing in mesh with the bevel gear on said hollow shaft; a second port in said vertical flange communicating with the upper end of said runner, and a conduit extending from said second port to a point adjacent the point of mesh between said bevel gears for discharging oil onto said gears at said point when said runner is actuated by rotation of said hollow shaft.

5. In a construction as defined in claim 4, a centrally apertured horizontally disposed cap above the bearing carried by said horizontal flange, said cap being formed with a depending annular flange secured to said horizontal flange outwardly of the bearing carried by the latter; the central aperture in said cap slidably embracing the uppermost end of said hollow shaft and the upper discharge end of the first mentioned conduit terminating within the area enclosed by said cap whereby the oil discharged into said area will cover the bearing below said cap.

6. A right angle pump drive comprising; a housing having lateral side walls, a bottom wall, and a top wall; a pair of vertically aligned bosses respectively formed on said top and bottom walls; a vertical driven hollow shaft rotatably extend-

ing through the upper boss of said pair and into the lower boss; a screw-type pump runner rotatably fitted within the lower boss of said pair and secured to said driven shaft; a pair of bearings for said shaft respectively supported within said bosses; the lower bearing of said pair extending over said pump runner; a horizontal drive shaft rotatably extending into said housing through one of said side walls; a pair of intermeshing gears respectively secured to said drive shaft and to said driven shaft between said pair of bearings; said lateral side walls, bottom wall, and the lower boss of said pair cooperating with each other to form an annular oil reservoir around said lower boss; an inlet port in said lower boss adjacent said bottom wall communicating between the lower end of said runner and the lower portion of said reservoir; an outlet port in the upper end of said lower boss communicating with the upper end of said runner; a conduit for oil extending from said outlet port through said top wall and opening at its upper end into the space above the upper bearing of said pair for conducting oil pumped by said runner to the upper end of the bearing of said pair for lubricating said latter bearing and passage of such oil by gravity past said bearing to the said gears therebelow and back to said reservoir.

7. In a right angle pump drive including a housing having lateral side walls, a bottom wall, and a top wall respectively supporting bearings rotatably supporting a horizontal drive shaft and a vertical, hollow driven shaft carrying gears in intermeshing relation within said housing; said bottom wall having a boss projecting vertically into said housing within the upper end of which is supported one of the bearings for said driven shaft; a screw-type pump runner for oil secured to said driven shaft within said boss and below said last mentioned bearing; a solid vertical shaft spaced within said driven shaft secured at its upper end to said driven shaft at a point adjacent the bearing in said top wall that supports said driven shaft and extending through said boss outwardly of said bottom wall; a vertical sleeve having a radially extending flange around its lower end; said flange extending across the lower end of said drive shaft and pump runner and firmly secured on its outer edges to said bottom wall; said boss, bottom wall and side walls cooperating to form an annular oil reservoir around said boss and an inlet port and an outlet respectively, communicating between said reservoir and the upper and lower ends respectively, of said runner; said sleeve being spaced within said hollow shaft and said bearing and spaced around said solid shaft and terminating at its upper end above the level of oil adapted to be held in said reservoir thereby forming a frictionless oil seal between said oil reservoir and said hollow and solid shafts preventing leakage of oil around said hollow shaft and through said bottom wall to outside said housing.

8. In a right angle pump drive including a housing, and a drive shaft and a vertical driven shaft extending perpendicularly to each other into said housing with intermeshing gears secured on said shafts respectively within said housing; a ball bearing including an inner and an outer race, supported within the upper end of said housing mounting the upper end of said driven shaft above said gears; means for supplying oil to the upper side of said bearing for

flowing by gravity between said inner and outer race and for dropping directly from the space between said races; an annular disk centrally secured on said driven shaft projecting horizontally therefrom radially outwardly beyond the downwardly projecting area below said inner race and the space between said races for directly receiving on its outer marginal portion the said oil that is adapted to drop directly from said space whereby said oil will be relatively violently flung generally radially outwardly of said disk when

said drive and said driven shaft are rotated; said disk extending radially outwardly over the said gear secured on said driven shaft, and a pair of spaced bearings in said housing supporting said drive shaft for rotation; and means positioning said bearings radially outwardly of said driven shaft and at a level below said disk so that oil flung directly from said disk will fall between said pair of bearings.

10

FRANK BABBITT DRAKE.
